UNITED STATES PATENT OFFICE.

ALFRED J. WEBSTER, OF COLUMBUS, OHIO, ASSIGNOR TO JOSEPH A. JEFFREY, OF COLUMBUS, OHIO.

CONVEYER.

No. 811,190.

Specification of Letters Patent.

Patented Jan. 30, 1906.

Application filed December 2, 1897. Serial No. 680,638.

To all whom it may concern:

Be it known that I, ALFRED J. WEBSTER, a citizen of the United States, residing at Columbus, in the county of Franklin and State of Ohio, have invented certain new and useful Improvements in Conveyers; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 Figure 1 is a side elevation of a sufficient portion of conveyer mechanism to illustrate the manner of applying my improvements. Fig. 2 is a plan view thereof. Fig. 3 is a cross-section on the line $x-x$ of Fig. 1 and on an enlarged scale. Fig. 4 is a cross-section of the conveyer-trough. Fig. 5 is a face view of one of the flights on a still larger scale. Fig. 6 is a plan view of a series of the chain-links and one of the flights. Fig. 7 is a side 25 view of the same. Fig. 8 is a vertical section showing a slightly-modified construction.

The operative parts of the conveyer are supported upon a framework, which it is not necessary to describe in detail, inasmuch as 30 it may be varied according as circumstances or preference may dictate. This framework is indicated as a whole by A, it having at the ends chain-wheels B B', one of which is adapted to have power applied to it from an engine or other motor. C indicates the chain which is mounted upon these wheels and by which power and motion are imparted to the devices which effect the propelling of the material along the conveyer.

40 Upon the framework above referred to there is supported a trough (indicated by D) and having the side walls $d-d$ and the bottom walls d' . These are preferably formed of sheet metal, the side walls being fastened to the 45 stringers a and the bottom walls d' inclining downward toward the central line, where they are supported upon the bottom stringer a' .

The chain C is arranged to move centrally through this trough D. It is constructed as 50 follows: It is formed of alternate single-bar and double-bar links $c-c'$. The single-bar link c is formed, as shown, with pintle-apertures c^2 at the ends and with an intermediate transverse aperture c^3 . The double-bar link

c' is formed of two side bars $c^4 c^4$. These bars overlap the ends of the single-bar links c , and they are connected thereto by the pintles F. Each pintle is formed with a web f, which engages in a recess formed at the side of the pintle-aperture in the side bar c^4 , and after the pintle has been inserted and riveted or otherwise fastened it is locked by its web f to the double-bar link so as to be incapable of rotation relatively thereto. The pintle-apertures c^2 in the single-bar link are formed so as to fit with the utmost nicety the pintles F, and in this way sand, grit, and foreign materials are excluded from the journal part of the wearing-surface of the pintle.

55 By having more or less of the pintle relatively flattened or web-like, as at f, and fitting it into the correspondingly-shaped pintle-seat in the link c' I prevent it from being worn or cut in the relatively short apertures of the side bars $c^4 c^4$ and compel the rocking 60 and bearing to take effect along the enlarged cylindrical wearing-surfaces at the central part of the pintle.

70 G indicates the flight. As shown, it is formed with an upper part and a lower part 80 adapted to project from the chain—one upward and the other downward—and in order to have the flight held properly by the trough so as to prevent torsion upon either the flight or chain I have the working edges of the flight 85 converge or incline toward the central line to correspond with the bottom walls of the trough, and the upper edges of the flight can be similarly shaped, so that it can operate along its return run in an upper trough. 90 Moreover, by having the edges of the flight and the bottoms of the troughs shaped in this way the material is carried toward the central line and prevented from accumulating in the corners, this being, however, an old and well-known feature of construction and arrangement, broadly considered.

95 The chain being made of straight steel or iron bars, (in order to have the links exceedingly strong,) it is difficult to form thereon 100 attachment-lugs for securing the flight. I provide an attachment, such as herein shown at H. It is formed with a tubular socket part h, having an aperture in which the single-bar link c can be snugly fitted and has laterally-projecting lugs h', by which it is riveted to the flight. It is secured to the link c by means of a bolt or pin I, for which an aper-

ture c^3 is formed in the link and in the socket part h of the attachment.

The aperture in the flight is of a size and shape to accurately fit the link c , to which it is attached, and this link is of a size and shape to permit the flight to be readily passed over it longitudinally to the place of attachment. As is shown in the drawings, the link c is of uniform size and shape from end to end. This construction of the flights and of the flight-carrying links permits of each of these parts being made integral. It also permits of the easy removal and replacing of any flight, it being necessary only to uncouple the chain at one of the joints of the flight-carrying link, when the flight may be removed or put in place without further separation of parts. Heretofore it has been customary to make either the flight-carrying link of two or more separable parts and to provide means for securing such parts together with the flight between or upon them or else to make the flight of two or more separable parts adapted to be secured together, so as to embrace the flight-carrying link to which it is thus secured. The construction which I have invented makes not only a more simple construction, but one which is stronger, in that both the flights and the flight-carrying links are of integral construction.

Heretofore it has been customary to guide and support flights of this character by so constructing them that they could engage at their ends with the trough or with guideways along the sides thereof. Difficulty is experienced with constructions of that character when a single chain is used, owing to the liability of the flights to be cramped at one or both ends either when twisted under the strain of the load or when shaken, jolted, or otherwise crowded toward one side or the other. I have obviated this by employing a single central guide at the working edge of the flight adapted to engage with a single guide-iron along the center of the trough. As shown, this consists of a lug J , which is formed with a groove or concave way j . It has a flange or lip j' , provided with apertures by which it can be riveted to the flight. The guide part proper, j^2 , is elongated so as to provide a long bearing which will hold the flight from twisting and keep it steadily in line. On the bottom of the trough there is secured a guide-strip K , whose outline in section corresponds with that of the guide-piece j^2 . It will also be observed that the guide K constitutes a support arranged to hold the flights and chain out of wearing contact with the trough, thus enabling me to use for the side and bottom walls of the trough much lighter material than can be employed when the flights run in sliding and wearing engagement therewith, as is now ordinarily the custom. When this feature of my invention is applied to a conveyer, the endless carrying member

of which is a single chain, I find that the best results are secured when a single support is employed and arranged, as shown in the drawings, that is, in the bottom of the trough and directly below the chain. However, this feature of the invention is not limited to the particular arrangement or number of supports which have the function of supporting the moving parts of the conveyer out of sliding engagement with the trough.

When the conveyer is in motion, the guide-pieces j^2 successively engage with and ride along on the guide-strips K , and the flights are properly held thereby, the flights normally moving toward the left, as seen in Figs. 1 and 2.

When duplex flights are employed, such as shown—that is to say, with two working edges—one for the lower trough and one for the upper, each edge is provided with a guide of the character described, the upper one in the drawings being indicated by J' , it being similar to that described at J .

In structures where but one trough is employed, but where it is desired to support the idle run of the conveyer, a guide for the flights can be used, such as shown at K' , similar to that at K , but supported independently of a trough. In such case the flight can be of modified shape, if the edge which extends downward on the upper run is not used for conveying purposes.

As shown, the bottom edge of the flight is cut out or provided with a recess at its wider central part, and the guide-block is secured adjacent thereto, so that the guide proper at j^2 will register with the recess or cut-away portion on the edge of the flight.

I am aware of the fact that chains with flights have been heretofore made by casting the flight integrally with the links of the chain and also that conveyers have been made by securing the flights at their edges to the chains; but when the conveyer is made as herein provided flight relatively thin sheets of metal can be employed, and firm fastening to the chain can be provided by such attachments as at H , which brace the sheet metal and distribute the strain from the chain, and a strong support for the edge of the flight can be provided by such attachment, as at J , which is so arranged as to take the thrust off from the edge of the sheet metal, this support, as well as the attachment H , both being in the central longitudinal planes of the conveyer, and between the ends of the flights, and as both of the attachments are on the rear side of the flight the front faces of it can be left comparatively smooth and unobstructed for engagement with any of the material that is being conveyed.

What I claim is—

1. In a conveyer, the combination with the chain, of the flights formed of sheet metal secured to the chain and extending both above

- and below the chain, guides secured to the outer edges of the flights, and substantially in the longitudinal plane of the chain, and a stationary guide with which the flight-guides engage, substantially as set forth.
2. In a conveyer, the combination of a chain, a series of flights secured thereto, guides carried by the flights and arranged in substantially the longitudinal plane of the chain, and a stationary supporting-guide with the upper surface of which said flight-guides engage arranged in a plane different from that in which the chain moves, the said guides being arranged to support the flights from sliding engagement with the trough, substantially as set forth.
3. In a conveyer, the combination of a trough, an endless chain, a series of flights secured to the chain, the chain being above the working edge of the flights, and the chain and flights normally tending under the action of gravity to press toward the bottom of the trough, and a support and guiding bar with which the flights engage, said bar being arranged in substantially the vertical plane of the chain and projecting above the top of the trough-bottom, substantially as set forth.
4. The combination of a trough, the chain arranged to move adjacent to the trough, a series of flights rigidly connected to and carried by the chain, a series of guides secured to the working edges of the flights, and a stationary guide for supporting the flights above the bottom of the trough with the upper surface of which the flight-guides engage, the chain being so connected with the flights as to be situated above the stationary supporting-guide, substantially as set forth.
5. The combination of a trough, a stationary guide arranged in the bottom of the trough and projecting above the lower portion thereof, the chain arranged to move adjacent to the trough, and a series of flights carried by the chain, the working edges of the flights being constructed to engage with the stationary guide in the bottom of the trough, substantially as set forth.
6. In a conveyer, the combination of a trough having side walls and a bottom wall, an endless chain, flights rigidly secured to the chain and arranged to normally bear down toward the trough-bottom under the gravity of the chain, and a supplemental support for the flights and the chain situated between the ends of the flights substantially parallel with the trough and arranged to sustain the flights and chain out of wearing contact with the trough, substantially as set forth.
7. In a conveyer, the combination of an endless chain, flights secured to the chain, a trough through which the flights move having side walls and bottom walls sloping toward the center, and a supplemental flight-support arranged centrally of the trough and having an upwardly-extending convex bearing-face adapted to maintain in conjunction with the trough-bottom an unbroken surface for supporting the material and arranged to sustain the flights out of wearing contact with the trough-bottom, substantially as set forth.
8. In a conveyer, the combination of a trough having side and bottom walls formed of sheet metal, and a central guiding and weight-supporting bar supported independently of the walls of the trough and arranged between sections of the bottom of the trough, substantially as set forth.
9. In a conveyer, the combination with a trough, of an endless moving carrier member, and flights secured thereto and arranged transversely to the carrier member and having at their lower edges shoe-like supports arranged to support the flights and carrier member and hold the lower edges of the flights out of scraping contact with the trough, substantially as set forth.
10. In a conveyer, the combination with the trough for supporting the material, of a stationary supporting-guide situated along the central longitudinal lines of the trough, a single chain in the center, longitudinally, of the trough and above the guide, and the flights secured to said single chain, each flight having an elongated guide at its center transversely, and arranged to rest upon the upper surface of the central supporting-trough guide, substantially as set forth.
11. In a conveyer, the combination with the trough having a stationary guide on its central longitudinal line, the movable flight, and the chain secured to said flight, of the guide secured centrally to the lower edge of the flight and having the elongated guide part adapted to engage with the trough-guide, substantially as set forth.
12. In a conveyer, the combination of a chain having alternate double-bar links *c* and single-bar links *c'*, of the flights, and the flight attachments *H* secured to the single-bar links, each formed separately from its link with a tubular socket *h* through which the link is passed, the bolt for fastening the socket to the bar, and each attachment fastened to its flight, substantially as set forth.
13. In a conveyer, the combination with the chain, of the flight which widens from its ends toward its center and having a recess cut out of its lower edge, and a guide-block secured to said lower edge and having an elongated guide with a passage registering with the recess on the edge of the flight, substantially as set forth.
14. In a conveyer, the combination of the flight or material transporting device, the separately-formed attachment joined to the flight for securing it to the chain, the link *C* adapted to be secured to the said attachment and formed with the pintle-aperture *c*, the link *c'* having the side bars *c*, *c'*, with pintle-

apertures near the ends, and the pintle F having the central cylindrical rocking bearing-surface within the pintle-aperture at c^3 in the link c and having the flattened or web-like parts fitting to the correspondingly-shaped pintle such as in the side bars c^1 , c^2 , and said pintle at the ends being upset or riveted, whereby the material transported by the conveyer is prevented from entering the pintle-seats and the pintle is compelled to rock in the central link-bar C, substantially as set forth.

15. In a conveyer, the combination of flights having apertures through their central portions, and a chain formed of articulated links, comprising flight-carrying links of a size and shape to fit the said apertures in the flights, and permit the flights to be passed longitudinally over the same from the ends of 20 the links to the places of the attachment of the flights thereto, substantially as set forth.

16. In a conveyer, the combination of a chain formed of articulated links, comprising flight-carrying links c formed of bars of uniform size and shape from end to end, and flights arranged to be secured to such links c, and having apertures through their central portions of a size and shape to closely fit the said bars, substantially as set forth.

30 17. In a conveyer, the combination with the flights, each narrowing from the center toward the ends transversely, and formed of relatively thin metal, and having an aperture

at the center, of a chain passing through the said central aperture, an attachment secured to each flight and secured to the chain, and supporting attachments for the flight secured to it at points between its ends, and in the vertical central longitudinal planes of the conveyer, substantially as set forth.

18. The combination with the flight and the chain passing centrally through the flight, of the attachment J secured to the rear side of the flight and adapted to support it against edge thrust, and the attachment H 45 secured to the rear side of the flight and secured to the chain, substantially as set forth.

19. In a conveyer, the combination of a chain, a series of transversely-arranged flights secured thereto, a stationary supporting-guide 50 arranged adjacent to and parallel with the path followed by the chain, and guides secured to the flights and arranged to engage with the said stationary supporting-guide, the guides carried by the flights being elongated in a direction parallel with the chain and having engagement with the stationary guide that tends to prevent twisting of the flights, substantially as set forth.

In testimony whereof I affix my signature 60. in presence of two witnesses.

ALFRED J. WEBSTER.
